DRAWERS

Antalné Fekete, Budapest, Hungary

Application March 30, 1933, Serial No. 663,606
In Hungary March 31, 1932

1 Claim. (Cl. 2-237)

This invention relates to drawers or pants, more particularly for gentlemen's wear, with the width of closure adjustable in steps and with a smooth back portion, characterized by a belt provided at 5 each end with an extension, a row of buttons sewn on to one end of this lengthened belt, the buttons thereon being equally spaced apart, and a row of button holes on the other end portion of the extended belt, the button holes also being equally spaced apart, and the distance between adjacent button holes being twice as great as the distance between adjacent buttons.

The drawers or pants thus constructed can be adjusted by the wearer to the size of his body 15 when he grows fatter or thinner, or after meals. Furthermore the garment according to the invention can be kept in stock in considerable quantities, since it can be regulated to different sizes.

One form of construction of the invention, as 20 applied to gentlemen's drawers, is illustrated by way of example in the accompanying drawing, in which

Figure 1 shows the garment buttoned up, while 25 Figure 2 illustrates the drawers in an unbuttoned condition.

The pair of drawers as illustrated in the drawing comprises a body having leg portions and provided with a slit opening in the front extending approximately to the crotch.

The waist-belt or girdle A of the drawers is 30 extended at both ends to form belt members or extensions a_1 and a_2 . To the belt A are sewn, at equal distances d apart, the distance d amounting to about three or four centimeters, a number of 35 buttons (preferably six or seven) $c_1, c_2, c_3, c_4, c_5, c_6$, while in the other extended end of the girdle A are formed button-holes f , the distance between

which is equal to $2d$. The number of buttons is at least twice as great as the number of button-holes.

Into the three button-holes f can be buttoned as required the buttons, c_1, c_3 and c_5 , or, as Figure 5 shows, the buttons c_2, c_4 and c_6 . If necessary only the buttons c_3 and c_5 or the buttons c_4 and c_6 need be employed.

The front opening or slit of the drawers is covered by the flap e at each adjustment.

The back portion of the drawers is smooth, whereby material is saved, and the cost of manufacture reduced. The garment according to the invention lies against the body without creases at every adjustment.

The garment according to the invention may also be employed as bathing drawers or as rowing shorts.

What I claim is:—

A pair of drawers comprising a body having leg 20 portions and provided with a slit on the front extending approximately to the crotch, a waist belt carried with the top of the body and having overlapping extensions projecting beyond the slit at the front, a row of buttons equally spaced apart 25 on the inner extension of the belt and the adjacent inner part of the belt, the outer extension of the belt and the adjacent main part of the belt having a series of equally spaced apart button holes, a flap secured to the lower edge of the inner 30 extension of the belt and to the adjacent edge of the slit in the body in order to form an inner closure for the slit in every adjusted position of the drawers and the distance between the adjacent button holes being twice as great as the distance 35 between adjacent buttons.

ANTALNÉ FEKETE.
